UNITED STATES PATENT OFFICE.

LOUIS STEINBERGER, OF NEW YORK, N. Y.

SOUND-TRANSMITTING MEMBER.

1,146,535.

Specification of Letters Patent. Patented July 13, 1915.

Application filed June 23, 1911. Serial No. 634,867.

To all whom it may concern:

Be it known that I, LOUIS STEINBERGER, a citizen of the United States, and a resident of the city of New York, borough of Brooklyn, in the county of Kings and State of New York, have invented a new and Improved Sound-Transmitting Member, of which the following is a full, clear, and exact description.

10 My invention relates to sound transmitting members, and in this instance is applied more particularly to telephone receiver casings and comprises certain structural improvements having quite a diversity of independent applications and separate objects, among the latter being the following: I. To improve the resonating properties of sound transmitting members generally; II. To improve the acoustical properties of receivers; 15 III. To strengthen the receiver casing along certain lines in which it is often subjected to undue strain due to shocks and jars; IV. To so economize the material of the casing by distributing a given quantity of it to 20 better advantage than usual; V. To improve the appearance of the receiver casing; and VI. To enable the operator to secure a firm grip upon the receiver casing.

25 One of the most important purposes of my invention is to improve the acoustical properties of the receiver which I do by giving to the receiver casing a certain appropriate form. In this connection I wish to call attention to certain facts not generally 30 known in acoustics, and particularly to acoustics as applied to the conditions associated with telephone receivers. In the first place the receiver generally comprises, among other things, a diaphragm chamber 35 bounded on one side by a diaphragm, and from this diaphragm the sounds are transmitted outwardly, that is, toward the ear of the person using the receiver. The diaphragm, however, while intended to throw off sound waves traveling in one direction only, does in fact throw off sound waves from each of its faces, and, consequently 40 these sound waves must depart in two directions from the diaphragm. The sound waves 45 which leave the inner face of the diaphragm spread out into the diaphragm chamber re-vibrating therein to a greater or lesser extent. The sound waves passing outwardly from the diaphragm, while, of course, intended primarily to reach the ear of the op-

erator directly, are nevertheless screened, in a measure, by the receiver cap, and this causes the sound waves to be reflected. The result is that sound waves on both sides of the diaphragm are again and again reflected 60 and practically baffled back and forth. Owing to this fact the solid portions of the receiver, and particularly the receiver casing, are necessarily thrown into vibration to a greater or lesser extent. The receiver casing, therefore, has a tendency to act as a sound board in accordance with recognized principles in acoustics, as will be understood from analogous facts in other arts dealing with sound controlled mechanisms. 70

It is well known, for instance, that in a musical instrument the vibration of a string, a diaphragm or a reed is readily communicated to any solid body on which the vibrating member is mounted or to which it is secured. It is also well known that certain shapes or forms for the solid body are more favorable than others in order to promote the vibration of the solid body or portion thereof in consequence of the vibratory movements of the vibrating member. I take advantage of the principle here referred to and so apply it as to promote the efficiency of the receiver. That is to say I give the receiver casing a special form or shape, one purpose of which is to render the casing sonorous, or in other words to make it act in some extent more or less analogous to the sounding board of a musical instrument. 85

In this connection it may be further noted that a vibratory member may communicate vibratory motion to a solid body much larger than the vibratory member conferring the motion, and that the sonorous properties acquired by the solid body may be present in a very considerable measure. For instance, a telegraph wire strung along the tops of heavy telegraph poles, whether made of wood or metal and having shapes not specially adapting them as sound boards or any equivalents therefor, nevertheless readily receive, and in turn readily transmit to the ear, such vibratory motions as may be communicated to the wire by mechanical means. Even if a slight wind is blowing across the wire and the wire thus thrown into vibration, the ear of the operator, if applied to the post, will readily hear sounds emanate directly from the post. These sounds are super-induced within the post by 100 105 110

the vibratory action of the wire. Again, a person placing his ear upon a railroad track may discover, by vibrations emanating directly from the latter, the proximity of a train which, however, is so far distant that sounds proceeding from it through the air are inaudible. Indians, by placing an ear upon the ground, are able to detect the presence of an animal or a person walking upon the ground, but located at a considerable distance. Facts of this kind could be multiplied indefinitely, but there appears to be no reason for pursuing this phase of the subject further. Suffice it to say that it is a principle well recognized in acoustics that a vibratory body subjected to vibrations set up by the expenditure of very little energy has, under favorable conditions, a marked tendency to communicate analogous vibrations to any solid body with which it is connected, and that the vibrations thus set up in the solid body constitute within themselves practically a local source of sound waves. These sound waves may be regarded as secondary sound waves, and my purpose in the present invention is to as far as practicable add their energies to that of the sound waves which proceed directly from the diaphragm to the operator's ear. This is easily accomplished. In the transmission of sound by telephone, and particularly in the transmission of speech, it is true that many of the vibrations transmitted are of comparatively short duration. It follows, as a consequence, that a lineal measurement of sound waves corresponding to the vibrations of short duration will show that the sound waves are in fact comparatively short. Nevertheless, in a telephone receiver the diaphragm and the parts associated therewith are very close together so that even if a sound vibration is communicated from the diaphragm to the casing, or to any other part of the receiver, and such casing or part in turn throws off sound waves, these sound waves in practice reach the ear of the operator so closely behind the respective sound waves directly from the diaphragm that the effect upon the operator's ear is substantially the same as if the original or primary sound waves, proceeding directly from the diaphragm to the ear, were reinforced or strengthened by the sound waves emanating directly from the receiver casing or other parts immediately associated with the diaphragm.

The receiver casings ordinarily used in this art are not at all suitable for promoting the effect just described. Generally, a receiver casing is made quite thick and so formed as to be grasped easily and pressed against the ear, but has no shape specially adapted for subjecting the receiver casing or any part thereof to the vibration of the diaphragm so as to cause the receiver casing

or part thereof to become *per se* a vibratory or analogous member. Indeed, in ordinary practice the receiver casing is made smooth, and throughout most of its length is, in many instances, of substantially cylindrical form. The operator holding the receiver in his hand, grasps it much as he would a cylindrical handle, that is to say, his fingers and thumb freely encircle the receiver casing and as far as practicable tends to envelop most of the outer surface of the latter, so that the skin and flesh of the operator's hand constitute a sound deadening material and the receiver casing has little or no opportunity to vibrate, the result being that sounds heard by the operator and coming from the receiver are produced entirely, or almost so, by the diaphragm acting directly upon the air.

What I seek to do is to promote the formation of sound vibrations within the receiver casing in order that this casing may act as a sound board and thus reinforce the vibratory action of the diaphragm. I further seek to sub-divide the receiver casing into a number of articulate portions which, though integral with each other, are, nevertheless, adapted to vibrate independently of one another. By doing this I promote the formation of vibratory motion in one part of the receiver casing, even though an analogous part happens, owing to some accidental cause, to be restricted in its vibratory motion.

Aside from the purpose above expressed, I seek by giving the receiver casing a suitable form for carrying out the objects above stated, to strengthen the receiver casing and add to its ornamentation, and finally enable it to be made with a minimum of material.

Reference is to be had to the accompanying drawings forming a part of this specification in which similar characters of reference indicate corresponding parts in all the views, and in which—

Figure 1 is a perspective showing my improved receiver casing and its cap; Fig. 2 is a section through the receiver casing; and Fig. 3 is a substantially central vertical view through the receiver complete, the casing being in section.

The receiver casing comprises a body portion 3 having roughly a horn shape, and provided adjacent its smaller end with an enlarged portion 4, and at its larger end with an enlarged annular portion 5. The body portion 3 is further provided with a number of ribs 6 spaced equi-distant, each rib being of slightly less diameter at its end adjacent the smaller end of the body portion 3 than at its opposite end. The ribs are also spaced farther apart at their ends adjacent the large annular portion 5. Each rib 6 is provided with rounded ends 7, 8 terminating close to the respective ends of the body por-

tion 3. A receiver cap 9 is secured upon the enlarged annular body portion 5 in the usual or any desired manner. The body portion 3, at its smaller end, is provided with an aperture 10 bounded by a raised bead 10^a. This aperture is used for leading the cords or other conductors into the casing. The body portion 3 is provided intermediate the ribs 6 with grooves 11, the concave surfaces of which merge into the convex surfaces of the grooves and form continuations thereof so that the exterior of the body portion 3 is fluted, that is, provided with a surface which, as seen in cross section (see Fig. 2) is undulating in form. The inner surface of the body portion 3 is provided with grooves 11^a, as will be understood from Fig. 2. The grooves 11^a are spaced apart, and between them are surfaces 12^a of arcuate form, as seen in cross section; that is to say, the interior surface of the casing seen in cross section, as indicated in Fig. 2, would be cylindrical except for the interruptions made by the grooves 11^a. These grooves 11^a being in juxtaposition to the grooves 11, the net result is that between the ribs 8 are thin walls each concave inside and also concave outside, these thin walls constituting very effective resonating members.

The receiver magnet is shown at 13, and at 14 is a cord (containing a conductor), the cord having two branches 14^a which lead to binding posts 14^b, the latter being in turn electrically connected by cords 14^c with the electro-magnet which may be of the usual or any desired construction. A metallic spider 15 is provided with openings 16 and with a ring 17. A diaphragm 18 engages the ring 17 and is held in position by the cap 9. When the diaphragm vibrates so that sound waves pass backwardly from it into the receiver casing, these sound waves usually pass through the openings 16.

By virtue of the thin walls between the ribs 6 being resonating members, as above described, these members vibrate freely in consequence of the motions of the diaphragm and the acoustical disturbances of the air column within the casing.

The operation of my device is as follows:—The receiver is, to all outward appearances, used in much the same manner as any other receiver; that is to say, the operator, in order to hear sounds reproduced by the receiver, merely grasps the receiver in his hand and presses the larger end of it to his ear. In doing this his hand of course touches the outermost portions of the ribs 6, but not the bottoms of the grooves or channels 11, which thus extend, unobstructed, entirely under the operator's hand.

The vibrations set up in the diaphragm by electro-magnetic action, as well understood in this art, cause the diaphragm to throw

off, sound waves in two directions. These sound waves tend to cause the body portion 3 of the receiver casing to vibrate. The pressure of the operator's hand upon the outermost portion of the ribs 6 tends, in a measure, to prevent the vibrations from developing in the body portion of the casing. The vibrations, however, are comparatively free to develop in those parts of the body portion located between the ribs 6; that is to say, the bottoms of the grooves 11, where the material is comparatively thin, are not restricted directly by contact with the operator's hand and are, therefore, free to vibrate. Moreover, being separated from each other by the ribs, they are free to vibrate independently of each other. If, therefore, it happens that the pressure of a finger or any portion of the operator's hand prevents some one or more of the thin vibratory portions of the casing from vibrating freely, this does not prevent other sonorous portions from properly performing their functions. The result is that the receiver casing above described, performs to some extent the office of a sounding board or sound box. The vibratory portions of the casing, when actuated as stated, throw off sound waves, and these reach the ear of the operator. I avail myself, too, in this connection of another principle of recent years recognized in acoustics, that is, if a sonorous member be given a horn-like shape or form, and then made to vibrate, the sounds which it produces are oftentimes more natural than the same sounds would be if made without the aid of the member of horn-like form. It will thus be seen that my receiver has roughly the form of a horn-like member and is provided with articulate portions extending practically the full length of the horn-like member and specially adapted to become, each respectively, the seat of vibratory activity.

Owing to the resonating properties of the receiver built as above described, and particularly to the secondary vibrations set up in the resonating members bounded internally by the grooves 11^a and externally by the grooves 11, the loudness and clearness of the sounds made by the telephone as a whole are greatly improved. I am aware that receivers having roughly a horn-like form have heretofore been operated and used. The operation above enunciated, however, was missing from the receivers mentioned, owing to the fact that such receivers did not have any portion or portions specially adapted for receiving and throwing off vibratory impressions.

It will be noted that the receiver casing is greatly strengthened by the ribs 8. Each rib has a form specially adapted for enabling the receiver casing to resist the destructive effects of shocks and jars. For instance, the

thickened and larger portions of the ribs are disposed in close proximity to the annular enlarged portion 5, which, as experience shows, is subjected to considerable danger 5 of breakage. Persons handling the receiver carelessly are apt to swing the enlarged end against the wall or strike it against the telephone casing box. Since it is the larger end that receives the greatest shocks, the 10 strengthening effect of the ribs is greater at said enlarged end. Further, the ornamentation of the receiver casing is enhanced by the addition of the ribs 6, and by the rounding of the ends of said ribs, the distribution 15 of the ribs so that the general curvature thereof approximates the general curvature of the outer surface of the receiver casing in the general direction of the length thereof, and the gradually increasing of the 20 diameter of each rib toward the larger end thereof. Last, but not least, the form given to the receiver casing enables it to be made from a minimum of material. Pound for pound of the material, the receiver casings 25 made from it are greater in number, strength, and other things being equal, if the receiver casings made from the material be constructed as above described.

I do not limit myself to the use of any 30 particular material to be employed in the construction of this receiver casing, though I prefer to employ the material commonly known in commerce as "electrose." Neither do I limit myself to any particular distribution 35 of the ribs 6, nor to the articulate portions intermediate these ribs, nor to any exact shape of the receiver casing, except as limited by my claims. Neither do I limit myself to any particular use for my 40 invention, nor to its employment upon telephonic receivers, as obviously the same principles may be extended to other articles and apparatus to which the principles above described have any particular application.

45 Having thus described my invention, what I claim as new and desire to secure by Letters Patent is:—

1. A receiver casing comprising a body portion provided externally with ribs, and 50 with vibratory portions disposed intermediate said ribs.

2. A receiver casing comprising a sonorous body to be held in the hand, said sonorous body being provided externally with ribs 55 extending in the general direction of its length.

3. A receiver casing comprising a sonorous body portion provided with articulate portions, said articulate portions being thin for 60 the purpose of serving as seats of vibratory motion.

4. A receiver casing comprising a longitudinal body portion provided practically throughout its length with vibratory portions independent of each other.

5. A receiver casing comprising a body portion provided with ends, one end having a greater diameter than the other, said body portion being articulated and rendered thin at independent points for the purpose of 70 facilitating the independent vibration of different parts of said body portion.

6. A receiver casing comprising a body portion provided with an enlarged end having generally an annular form, said body 75 portion being further provided with external ribs integral with it and extending in proximity to said enlarged end, said ribs being thickened at the points adjacent said enlarged end.

7. A casing comprising a body portion provided with external ribs and further provided with internal grooves opposite to said external grooves, and mechanism within said body portion for producing sound vibrations.

8. A sound transmitting member comprising a hollow casing provided internally with grooves, the wall of said casing being relatively thinner along said grooves and adapted to vibrate, and a diaphragm mounted within said casing for producing acoustical disturbances therein.

9. A sound transmitting member having generally a horn-like form and provided internally with grooves extending longitudinally thereof, the wall of said member being relatively thinner along said grooves and adapted to vibrate, and mechanism mounted within said member for producing acoustical disturbances therein.

10. A receiver casing comprising an elongated hollow body portion provided both internally and externally with grooves, the internal grooves mating the position of the external grooves in order to render the intervening portions of the walls of the casing sufficiently thin to vibrate, and a diaphragm mounted within said casing for the purpose of producing acoustical disturbances therein.

11. A receiver casing comprising a body portion provided externally with ribs, each of said ribs being wider at one end than at the other.

12. As an article of manufacture, a sound transmitting member of substantially horn-like form provided upon its external and internal surfaces with a plurality of grooves opposite to each other.

13. A receiver casing comprising a hollow body portion of substantially horn-like form, provided on its outer surface and also on its inner surface with divergent longitudinally extending raised portions, those on the outer surface being opposite to those on the inner surface throughout their extent.

14. A receiver casing comprising a hollow body portion having a plurality of exterior surface irregularities between which are sound vibratory portions, the surface irreg-

ularities serving to protect the vibratory portions when the receiver is grasped in the hand.

15. A receiver casing comprising a body portion provided externally with ribs extending longitudinally thereof, each of said ribs being wider at one end than at the other, and the material of the casing being continuous intermediate the ribs and being made thinnest centrally between said ribs and gradually rounding outwardly into said ribs throughout the length of said ribs.

16. A telephone receiver casing comprising a hollow body having relatively thick and heavy end portions and a relatively thin

intermediate portion, and a plurality of ribs extending longitudinally of said body integral with the thin intermediate portion thereof and said ribs having their opposite ends merging into the heavy end portions of the body whereby to serve as reinforcing means for the thin intermediate portion of the body.

In testimony whereof I have signed my name to this specification in the presence of 20 two subscribing witnesses.
